UNITED STATES PATENT OFFICE.

JAMES M. TRINER, OF CHICAGO, ILLINOIS, ASSIGNOR TO THE PELOUZE SCALE AND MANUFACTURING COMPANY, OF SAME PLACE.

DESIGN FOR A SUPPORTING-STEM FOR SCALE-PANS.

SPECIFICATION forming part of Design No. 29,064, dated July 19, 1898.

Application filed February 28, 1898. Serial No. 672,101. Term of patent 14 years.

To all whom it may concern:

Be it known that I, JAMES M. TRINER, a citizen of the United States, residing at Chicago, in the county of Cook and State of Illinois, have invented and produced a new and original Design or Useful Shape for a Supporting-Stem for Scale-Pans, of which the following, in connection with the accompanying drawing, is a full, clear, and exact specification.

10 The said drawing is a perspective view of a scale-pan-supporting stem embodying my design.

15 The leading features of my design consist of the bars A A and a cross-piece B joining them.

The bars A A are substantially parallel and cylindrical, and their lower ends are united by a cross portion C, thus making a substantially U-shaped member. At a point more 20 or less remote from the upper and lower ends of the bars A A is located the cross-bar B, whose ends conjoin with the bars A A, re-

spectively, while its mid-portion extends outwardly or laterally away from the bars A A and is formed with a perforated flat portion 25 b, while on either side of such flat portion is formed an inward curve, as clearly shown in the drawing, the bar B being of greater vertical than lateral thickness.

The cross portion C is perforated laterally 30 at c, while the bars A A are each perforated at right angles to the perforation c at the points a, adjacent to the portion C and a', adjacent to the cross-bar B.

Having thus described my invention, what 35 I claim as new therein, and desire to secure by Letters Patent, is—

The new and original design or useful shape for a supporting-stem for scale-pans substantially as herein shown and described.

JAS. M. TRINER.
